US00D805346S

(12) **United States Design Patent** (10) **Patent No.:** **US D805,346 S**
(45) **Date of Patent:** **** Dec. 19, 2017**

(54) **COVER**

(71) Applicants: **Delvin Ryan**, Barrington Hills, IL (US);

Lorenzo Porcelli, Tarry Town, NY
(US)

(72) Inventors: **Delvin Ryan**, Barrington Hills, IL (US);
Lorenzo Porcelli, Tarry Town, NY
(US)

(73) Assignee: **Columbian Home Products, LLC**,
North Barrington, IL (US)

(**) Term: **15 Years**

(21) Appl. No.: **29/535,143**

(22) Filed: **Aug. 4, 2015**

(51) LOC (10) Cl. **07-02**

(52) U.S. Cl.

USPC **D7/395; D8/322**

(57) **CLAIM**

The ornamental design for a cover, as shown and described.

DESCRIPTION

FIG. 1 is a front perspective view of a cover;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines, shown from FIG. 2, are shown for the purpose of illustrating parts of the cover that form no part of the claim.

1 Claim, 5 Drawing Sheets
